UNITED STATES PATENT OFFICE.

EARL P. KILCOYNE, OF CAIRO, ILLINOIS.

SUSPENSION MEANS FOR ELEVATORS.

996,861.

Specification of Letters Patent.

Patented July 4, 1911.

Application filed December 8, 1910. Serial No. 596,365.

To all whom it may concern:

Be it known that I, EARL P. KILCOYNE, a citizen of the United States, residing at Cairo, in the county of Alexander, State of Illinois, have invented certain new and useful Improvements in Suspension Means for Elevators; and I do hereby declare the following to be a full, clear, and exact description of the invention, such as will enable others skilled in the art to which it appertains to make and use the same.

This invention relates to elevators such as are used to carry weights of various kinds up and down in buildings and it has special reference to a novel suspension means adapted to be attached to any size elevator so that certain weight indicating mechanism illustrated in my co-pending patent bearing the Serial No. 570,167 may be applied thereto.

The principal object of the invention is to provide a novel arrangement by which a weighing device may be attached to any size of elevator within reasonable limits so that it will not be necessary to build the device integrally with the elevator.

With the above and other objects in view the invention consists in general of certain novel features of construction, and combinations of parts illustrated in the accompanying drawings and hereinafter specifically described and claimed.

In the accompanying drawings, Figure 1 is a view showing the interior of an elevator shaft with an elevator car therein provided with the improved suspension means. Fig. 2 is a disassembled view of certain details used to adjust the device to different sized elevators. Fig. 3 is a perspective view of certain other details used in the adjusting of the device.

The numeral 10 indicates in general an elevator car and 11 the guides therefor. The attaching frame comprises a pair of brackets 13 which are secured opposite each other to the side members 12 of the elevator frame. The outer faces of these brackets are concave. At 14 are indicated arms which have ends 15 formed with convex faces which fit the concave faces of the brackets 12. Connecting the upper ends of these arms 14 and pivoted thereto is a cross bar 16 which forms the top member of the frame and on which the parts of the weighing mechanism are all supported. The ends 15 and brackets 13 are provided with suit-

able bolt holes for the reception of securing bolts 17, the holes in the ends 15 being tapered to permit of movement of said ends relative to the brackets 13. In order to relieve the strain from these bolts 17 the members 15 are provided at their lower ends with eyes 18 whereto are attached the ends of a bridle rope 19 which extends down the sides and underneath the bottom of the elevator, being supported at intervals by suitable brackets 20. On the arms 15 are provided guides 21 which embrace the guides 11 of the elevator well and below these guides are other guides 22 arranged for a similar purpose. In order to hold the arms 14 perfectly rigid a cross brace is provided which consists of a pair of members 23 each having one end firmly fixed to a respective arm 14 and having the opposite ends overlapping and provided with meshing teeth 24. These teeth are held in mesh by means of suitable clips 25 provided with set screws 26, the clips surrounding the members 23 and the set screws being screwed up to force the teeth firmly together. In order to lift the device when the same is not in an elevator well the members 14 are further provided with eye-bolts 27. It will thus be seen that by properly proportioning the length of the bridle rope the hanger of the device may be adjusted to any height of elevator while the adjustment of the members 23 permits the same to be set to any width of elevator, the concave and convex members allowing for this.

In order to suspend the device the member 16 is provided with a suitably disposed central opening through which passes a suspension bar 28 carrying on its lower end a spring seat 29. The member 16 is also provided with a spring seat 30 and between the two spring seats is a spring 31. Rack arms 32 extend upward from the spring seat on the suspension bar and serve to actuate weight indicating mechanism indicated in general at A and B.

There has thus been provided a simple and efficient device of the kind described and for the purpose specified.

What is claimed is:

In a device of the kind described, a pair of brackets adapted for attachment to an elevator car and provided with concave surfaces, a pair of bars having convex portions adapted to fit said brackets, a cross bar pivoted to the upper ends of the last mentioned

bars, a rack bar fixed to each of the pairs of bars, said rack bars being provided with teeth facing each other, clips surrounding the overlapping portions of the rack bars to hold the teeth in mesh, and a bridle rope having its ends secured to the respective bars of the first mentioned pair.

In testimony whereof, I affix my signature, in presence of two witnesses.

EARL P. KILCOYNE.
